UNITED STATES PATENT OFFICE.

FREDERICK A. MEYER, OF NEW YORK, N. Y., ASSIGNOR OF TWO-THIRDS TO MARSHALL LEFFERTS AND JOHN A. LEFFERTS, OF SAME PLACE.

LIQUID-FUEL INJECTOR.

SPECIFICATION forming part of Letters Patent No. 253,216, dated February 7, 1882.

Application filed June 18, 1881. (No model.)

To all whom it may concern:

Be it known that I, FREDERICK A. MEYER, of the city, county, and State of New York, have invented an Improved Liquid-Fuel Injector, of which the following is a specification.

This invention relates to that class of devices that are designed for the injection, in combination with a jet of steam, of petroleum or other liquid fuel into furnaces or fire-boxes.

10 The invention consists of a double hemispherical covered vessel, having a steam-space between its outer and inner shell, provided with an internal diaphragm to effect the better mingling of the steam and liquid fuel, with a receptacle for receiving the excess of oil or liquid fuel that may at any time enter the injector, and provided with a relief-pipe for the escape of such of the oil that is there vaporized, and provided with suitable discharge-nozzle, with 15 20 25

valved oil and steam supply pipes, and with an adjustable steam-pipe that controls by valvular action the admission of the liquid fuel or oil into said injector, all of which will be hereinafter set forth.

25 Figure 1 represents a sectional side elevation of the device. Fig. 2 is an enlarged side elevation of the bushing and connections.

Similar letters of reference indicate corresponding parts.

30 In the drawings, A represents the injector, of hemispherical shape, consisting of two hemispherical shells, A' A², screwed together, the one outside and over the other, with a space, b, between them, the outer shell, A', being 35 screwed upon the annular shoulder a of the inner shell, A².

A cap, B, is screwed firmly down over the rim of the shell A², against the shoulder thereof, and suitable packing, if necessary, is introduced between them to make a tight joint. A chamber, c, is formed in one side of this cap B, for the introduction of the nozzle C, that is screwed thereon, and made more secure by a lock-nut, d, so as to project laterally from the 40 45 injector A, and also for affording a direct connection between the interior of the injector A and its nozzle C.

A pipe, D, having connected to it a steam-supply pipe, D', and provided with suitable

valves, gg, has one end entered into the steam-space b of the injector A, to heat and vaporize the oil that may fall into its reservoir h, which is formed by a perforated diaphragm, E, that is fixed within said injector A, above its bottom. The other end of the pipe D is connected 50 55 by a screw-bushing, k, with the top of the vertical tubular conductor F, whose reduced or contracted end is screwed centrally into the cap B, and communicates with the interior of the injector A. Said conductor F receives the 60 liquid fuel through a pipe, G, connected to its side, and provided with a valve, l, from some suitable reservoir.

Screwed perpendicularly through the bushing k is a small pipe, H, having a reduced conical tip, m, secured thereon. This pipe H can be primarily adjusted with its tip m at a suitable distance above the contracted end of the conductor F, to regulate in a measure the flow of liquid fuel into said injector A, and can 65 70 75 be afterward relatively adjusted, so as in effect to have a valvular action upon the fuel-supply pipe G by turning the bushing k, which has a right and left hand screw, and is provided with a collar, k', to which a wrench may be applied, so as to close or open the end of the conductor F, and thereby regulate the flow of fuel from pipe G.

Steam being applied through the pipes D' D, and the liquid fuel being turned on in the pipe G, the steam and fuel together enter the conductor F, whence the steam forces the fuel in fine spray upon the diaphragm K, that is suspended within the injector A from the cap B by rods m, and said steam, in combination with 80 85 the heat imparted by the steam entering the steam-space b, vaporizes said liquid fuel, and, mingled therewith, issues under pressure through a passage, n, in the cap c, into the nozzle C, and thence into the furnace or fire-box 90 to which this device may be applied. What liquid fuel enters the injector A and does not at once escape with the steam through the nozzle C falls upon the perforated diaphragm E, and thence into the receptacle h, where a portion of it vaporizes and gradually passes off through the opening in said diaphragm E and 95 out at the nozzle C, while the remainder is

forced by the pressure of steam within said injector A up the pipe o, into and out of the nozzle C.

Any condensed steam in the steam-space b 5 may be drawn off through the cock p.

This injector is simple, durable, and effective, and can be applied at small cost to any furnaces or fire-boxes. It is not liable to get out of order, and its fuel-feed can be adjusted 10 with the utmost nicety.

Having thus described my invention, I claim as new and desire to secure by Letters Patent—

1. A liquid-fuel injector constructed substantially as herein shown and described, consisting of doublehemispherical shell A' A², provided with cap B, and nozzle C, diaphragm K, conductor F, adjustable bushing k, and conically tipped pipe H, arranged as set forth. 15

2. In a liquid-fuel injector, the combination,

with the double shell A' A², having a steam-space, b, of the receptacle h, formed by the diaphragm E, substantially as herein shown and described, said receptacle being designed to receive the excess of fuel entering the injector, as set forth. 20

3. In a liquid-fuel injector, the combination, with the receptacle h, and diaphragm E, and double shell A' A², of the escape-pipe o, substantially as and for the purpose described. 25

4. In a liquid-fuel injector, the combination, with the cap B, provided with chamber c, communicating with the double shell A' A² and the interior of the injector, of the nozzle C, substantially as herein shown and described. 30

FREDERICK A. MEYER.
